UNITED STATES PATENT OFFICE.

JOSEPH W. MYERS, OF JACKSON, MICHIGAN, ASSIGNOR, BY DIRECT AND MESNE ASSIGNMENTS, OF ONE-THIRD TO JOSEPH H. MYERS, OF JACKSON, MICHIGAN; ONE-THIRD TO ARTHUR J. TUTTLE, OF DETROIT, MICHIGAN; AND ONE-THIRD TO AGNES W. MYERS AND JOSEPH W. MYERS, BOTH OF JACKSON, MICHIGAN.

FLATIRON.

Application filed January 8, 1925. Serial No. 1,186.

My invention relates to automatically regulated electric heaters, and a special object of my improvements is to provide a flatiron that is inexpensive to manufacture, rugged and durable in construction, economical in service and easy to handle, offering a wide range of selectivity in available working temperature, and that shall attain the selected temperature and maintain the same upon whatever kind of work it is used and whether it has been resting on its stand, or has just been brought to its working temperature from a cold start.

I attain these and other advantages in the apparatus illustrated in the accompanying drawings in which:—

Fig. 1, is a central longitudinal section of a flatiron embodying my invention.

Fig. 2, is a plan view of the same, the upper part of the cover with attached parts being broken away.

Fig. 3, is a plan view of the heating element, and temperature regulating apparatus attached thereto.

Fig. 4, is an inverted plan view of the apparatus of Figure 3.

Fig. 5, is a detail plan view, to an enlarged scale, of a portion of the handle and cover and the temperature indicating and adjusting device located at this place.

Fig. 6, is an inverted perspective view of the adjusting knob and spindle.

Fig. 7, is a perspective view of the temperature indicating pointer.

Fig. 8, is a sectional view similar to Figure 1, to an enlarged scale, portions being omitted, or broken away, to economize room, the section being taken in the plane indicated by the line, VIII., VIII. Figure 2.

Fig. 9, is a section on the line, IX., IX., Fig. 8, some of the parts being shown in a different position from that of Fig. 1.

a, is the metal base, or smoothing plate. This is provided with a cavity, a², extending inward from its upper surface near the center thereof.

b, is the top plate. This is of the approximately triangular shape of the lower plate, lies above the same and is secured thereto by bolts ab, ab, ab. The upper surface of the plate b inclines downward from a line a little beyond a central transverse line to the larger end as indicated at b¹, and is cut

away centrally at this end forming the slot, b², extending inward.

c, is the cover which extends over the plate, b, with its lower edge resting upon the surface of the plate, a.

d, is the handle having a horizontal lower bail by which it is secured to the cover, c, by a bolt, cd, and to the top plate b, by a bolt, bd. The last named bolt also secures the cover, c, in place upon the iron. e, e, are spacing washers interposed between the lower bail of the handle and the upper surface of the cover. f, is an index plate secured upon the upper surface of the lower bail of the handle by the bolts, bd and cd.

g, is a spindle extending vertically through coaxial apertures in the index plate, f, the lower bail of the handle, d, and the cover c, and provided at its upper end with a molded thumb piece, h, by which said spindle may be rotated. h¹, is a notch formed in the thumb piece h, at its lower end, (Figs. 1 and 6). j, is a pointer struck out of a sheet of metal having an aperture, j¹, therethrough, for the reception of the spindle g, and having a lug, j², at its rear end, turned up from the metal from which it is formed adapted to engage in the notch, h².

g², is a circular disc of sheet metal having a tubular extension, g⁴, rising from its center with its axis at an angle to the axis of the disc. g³, is a cotter pin securing the tubular extension, g⁴, and therefore the disc, g², upon the spindle, g. x², is a washer forming a collar around the spindle g, fitting in part into the aperture through the lower bail of the handle. x, is a spiral spring surrounding the spindle g, and interposed between the cover, c, and the washer, x².

The method of assembling the parts just described is as follows:—

The pointer, j, is first threaded upon the spindle, g, the lug, j², engaging in the notch, h². The washer, x², is then threaded upon the spindle and then the spring, x. The end of the spindle, g, is now passed through the aperture in the bail of the handle, d, the spring x passing through said aperture and the washer, x², engaging therein. The tubular extension, g⁴, is now engaged over the end of the spindle, g, and pressed onward, compressing the spring, x, and the cotter pin,

*g*³, is then forced through the holes prepared for it, securing all the parts together. This brings the end of the pointer, *j*, into position to pass over the scale, H. L., on the index plate, *f*.

The heating element, and its controlling apparatus, constitute a unitary structure which may be handled separately, and that may be easily removed for repairs and replaced, or another similar structure substituted. It is described as follows:—

m, is an upper, and *m*² a lower, mica plate having the shape of the plates, *a* and *b*, and cut away in part to correspond to the lower 15 cavity, *a*², in the plate, *a*,

*m*³, is an electric heating element interposed between the mica plates, *m* and *m*².

n, is a sheet metal plate turned over at its edges, as shown at *n*², *n*², Fig. 9, to strengthen and stiffen the same, and provided with an opening at its center.

The plate, *n*, is secured to the mica plates, *m* and *m*², with the heating element between them and extends along the bottom surface 25 of the plate, *m*², adjacent to the central opening therein. *q*, is a bimetallic strip secured at one end by the bolt, *r*, to the plates, *m*, *m*², and *n*, and constituting a thermostatic arm adapted to bend upward and downward 30 as its temperature changes, its free end travelling in the slots *b*², *a*² and openings through the plates, *m*, *m*², and *n*, *q*², is a flexible strip of a material that is a good conductor of electricity, such as brass, secured at one end by the bolt, *r*, and at the other end connecting with the outer end of 35 the arm, *q*. *q*³, is a contact point at the outer end of the arm, *q*.

s, is an elastic arm secured at one end by 40 the bolt, *r*, at the outer surface of the plate, *m*, and extending above the arm *q*. *s*², is a contact point on the arm, *s*, adapted to coact with the contact point, *q*³. The arm, *s*, rises up and is prolonged in the extension, *s*³, beyond the contact point, *s*².

The plate, *n*, extends upward to form the lugs, *n*³, *n*³, upon each side of its central opening.

t, is a lever extending on both sides of 50 the lever, *s*, and pivoted at *t*², in the upper ends of the lugs, *n*³, *n*³. *t*⁴ is a roller of insulating material upon the end of the lever, *t*, under the extension, *s*³, of the lever, *s*. The other end *t*³ of the lever, *t*, engages under the disc, *g*², and the turning of said disc by the thumb piece, *h*, and spindle, *g*, oscillates said lever about its pivots, *t*², *t*², to adjust the roller, *t*⁴, to different positions vertically.

60 The plate, *n*, is bent upward at *n*⁴ and then backward at *n*⁵, and then again upward at *n*⁶. The cover, *c*, is cut away to provide an opening just above the part, *n*⁵, of the plate, *n*, and *n*⁶ is so located that it will prevent the 65 part, *n*⁵, being bent downward by hitting

against the edge of the opening through the cover.

*p*³, *p*³, are two binding posts secured to, but insulated from, the portion, *n*⁵, of the plate, *n*, and extending through the opening 70 in the cover. *p*, is a conductor secured at one end to one of the binding posts, *p*³, and connecting with one end of the heating strip, *m*³. The other end *p*⁵, of the heating strip, *m*³, is clamped between the strip, *q*², and the 75 plate, *m*², and is in electrical connection with said strip and with the bolt, *r*.

The other of the binding posts, *p*³, is connected by a leading-in strip, *p*⁶, with the arm, *s*, the inner end of said strip being 80 clamped between the end of said arm and the plate, *m*, by the nut, *r*³, on the bolt, *r*, through insulating washers. The construction and arrangement being such as to insulate the arm, *s*, from the bolt, *r*.

It will be noted that the mica plates, *m*, *m*², carrying the heating strip between them, the stiffening and supporting plate, *n*, and the various levers secured thereto form a 90 unit construction, that may be handled, and sold separately, and that it is only necessary to arrange said plates symmetrically between the plates, *a* and *b*, and secure the last named plates together to assemble such unit into the iron.

The operation of the above described apparatus is as follows:—

The connecting cord is placed upon the binding posts, *p*³, *p*³. The current then flows through the heating strip, *m*³, to strip, *q*², bolt *r*, and arm *q*, to the contact point, *q*³, to the contact point, *s*², through arm *s* and strip *p*⁶ and out through the other binding post, *p*⁸.

As the temperature rises the thermostatic 105 arm, *q*, bends downward, the arm, *s*, following it because of its elasticity until the extension, *s*³, strikes against the insulating roller, *t*⁴, when the motion of the arm, *s*, is thereby arrested and the further movement 110 of the arm, *q*, carries the contact point, *q*³, away from the contact point, *s*², and breaks the circuit through the heating element.

The point at which this break occurs can be selected by turning the disc, *g*², by the 115 thumb-piece, *h*, thus oscillating the lever, *t*, to bring the roller to any position desired vertically. When the iron cools down, of course the arm, *q*, bends back and the circuit is again completed through the points, 120 *q*³, *s*².

The conducting strip, *q*², is provided to convey a part of the current so that the thermostatic arm, *q*, will not be heated by the current passing through it.

The plate, *b*, is reduced in mass toward its larger end by slanting its upper surface downward at *b*⁸, and by slotting it out at *b*², so that this end of the iron shall heat as fast as the other and the temperature of 130

the iron will be uniform and will be correctly regulated by the thermostat.

In manufacturing, the limits of temperature at which the thermostat functions can be regulated by bending the extension, s^3 , of the arm, s , up or down, as the circumstances may require.

I prepare the exposed surface of the plate, b , and cover, c , so that but little heat shall 10 be radiated therefrom.

The shape of the heating element brings a greater relative length of the conductor toward the point of the iron, so that the iron is apt to heat up first, of to a higher 15 temperature, at this point; to counteract this effect, I have reduced the mass of the plates toward their larger end.

What I claim is:—

1. In an apparatus of the kind described, 20 the combination of a heating element, and a thermostatic regulator therefor, united together to form an integral structure adapted to be removed and replaced as a unit.

2. In an apparatus of the kind described, 25 the combination of a heating element, and a thermostatic regulator therefor, having a constituent element in common so constructed and united as to form an integral structure that can be removed and replaced 30 as a unit.

3. In an apparatus of the kind described, the combination of a heating unit structure, and a structure forming a regulator for the heating unit, the elements of the heating 35 unit structure being clamped between elements of the regulator structure whereby the heating unit is strengthened and with the regulator structure forms a unitary integral structure that is strong and rigid.

4. In an apparatus of the kind described, the combination of a working plate, a , having a cavity extending from its upper surface, a heating element located above said plate, a thermostatic arm extending into said 45 cavity, an arm located above said heating element and adapted to co-operate with said thermostatic arm, said arms having a common base to which the heating element is secured.

5. In an apparatus of the kind described, the combination of a heating unit with two superimposed terminals, insulating means between said terminals, a thermostatic switch arm, carrying a contact, a second arm 55 carrying a coacting contact, and a single bolt binding said arms together, and one of said terminals to one of said arms and the other to the other of said arms.

6. In an apparatus of the kind described, 60 a spindle having a thumb piece on one end thereof, said thumb piece having a cavity in its inner end, a pointer having a lug turned up therefrom, said spindle engaging through an aperture in said pointer, and said lug engaging in said cavity, and means

for holding said pointer in engagement with said thumb piece.

7. In an electrically heated flatiron having an automatic apparatus therein for regulating its temperature, the combination of 70 an adjusting device located on top of and at the center of said iron, a thermostatically controlled arm forming part of said apparatus having its movable end located at a distance horizontally from said device, a second arm yieldingly pressing against the first named arm toward said end thereof to make electrical contact therewith, and a lever carrying a stop at one end, said stop being located in the line of travel of the end of 75 said second arm at one end and adapted to arrest the movement of said second arm to permit the first named arm to move away from it and interrupt the contact, said lever extending at the other end into position to be actuated by said device and being adapted to carry said stop to various positions to break said contact.

8. In an electrically heated flatiron, a 80 flat heating element, a circuit controlling apparatus for said element having a base plate, said base plate being secured to said element and extending to the rear edge thereof and serving as a strengthening means for said element, and attaching lugs for electrical connections secured at the rear end of said element and to said plate.

9. In an electrically heated flatiron, a flat heating element, a circuit controlling apparatus for said element having a base plate, 90 said base plate being secured to said element and extending to the rear edge thereof and serving as a strengthening means for said element.

10. In an electric iron, the combination of 95 a smoothing plate hollowed out from its upper surface toward its center, a heating unit including its insulating sheets lying upon the upper surface of said plate and directly in contact therewith, a plate secured to said unit within the hollow of said smoothing plate and acting to stiffen said unit, and a thermostat secured to said stiffening plate in the hollow of said smoothing plate for the purpose described.

11. In an electric iron, the combination of 110 a smoothing plate hollowed out from its upper surface toward its center, a heating unit including its insulating sheets lying upon the surface of said plate and directly in contact therewith, a plate secured to said unit within the hollow of said smoothing plate and acting to stiffen said unit, a thermostat secured to said stiffening plate in the hollow of said smoothing plate for the purpose described, and an upper plate lying upon 120 said heating unit and clamping it in place against the smoothing plate.

12. In an electric iron, the combination of 125 a smoothing plate hollowed out from its up-

per surface toward its center, a heating unit including its insulating sheets lying upon the upper surface of said plate and directly in contact therewith, a plate secured to said 5 unit within the hollow of said smoothing plate and acting to stiffen said unit, a thermostat secured to said stiffening plate in the hollow of said smoothing plate for the purpose described, and a binding post for said 10 heating unit secured to said stiffening plate.

13. In an electric iron, a heating unit and a temperature regulator therefor employing

a structural element in common aside from their mutual electrical connections.

14. In an electric iron, a heating unit and 15 a temperature regulator therefor so combined as to be structurally interdependent and to form a unitary structure removable as a whole whereby less parts are required were each of said elements to be functionally 20 complete when detached from the other.

In testimony whereof, I sign this specification.

JOSEPH W. MYERS.
